BOTTLE CARRIER

Henry E. Brunhoff, Wyoming, Ohio, assignor to
 The Brunhoff Manufacturing Company, Cincinnati, Ohio, a corporation of Ohio

Application June 22, 1940, Serial No. 341,930

4 Claims. (Cl. 224—48)

This invention relates to crates for bottles, and particularly to a hand crate adapted to clampingly confine a plurality of bottles in a compact grouped arrangement to facilitate storage, and provide a convenient carrier receptacle for a retail supply of beverage bottles.

The hand crate is preferably of wire work, and is of particular utility in handling and dispensing beverage bottled goods, preferably in retail lots, and providing an open crate to facilitate storage in a refrigerator for cooling the contents of the bottles. The bottles are unitarily grouped within the crates, securely clamped against dislodgment and rattling, the clamping organization providing bails for conveniently carrying the crated group of bottles.

It is an object of the invention to provide a hand crate for bottles or the like, preferably formed of wire work for securely and compactly confining a group of bottles for handling or storage with an approximate full exposure of the bottles to facilitate cooling.

It is another object to provide a strong and durable light-weight hand crate of low manufacturing cost, and which may be collapsed and folded into compact form for storage or shipment.

It is another object to provide a hand crate having interlocking carrying bails which may be erected for carrying the crate, or which may be claspingly interlocked one with the other, to form a compactly clamped storage crate for the bottles, and for stacking the crates with the bottles, one upon another.

Another object is to provide a hand crate having interlocking bails, the crate adapted to be retained in partially opened position for convenience in loading and unloading, and positively locked in closed position for carrying, by interlocking the bails.

Further advantages and features of the invention will be more fully apparent from a description of the accompanying drawing, in which:

Figure 1 is a perspective view of a hand carrier crate, enclosing a group of bottles and clamped in closed position.

Figure 2 is an end view of a crate with the bails erected in carrying position.

Figure 3 is a perspective view of the crate in opened position to receive the bottles.

Figure 4 is an end view of an upper portion of the carrier, showing the bails interlocked, one of the bails serving as a carrier handle, and the other as a hasp for locking the crate in closed position for carrying.

Referring to the drawing, the crate constitutes a base 1 of tray form, preferably of sheet metal and of a size to accommodate the desired number of bottles, in the present instance six bottles arranged in two rows of three bottles each. The

base is preferably rectangular in shape, and includes side and end walls 2 and 3, respectively, which serve to enclose the lower portions of the bottles and retain them snugly within the base. 5 The side walls 2, 2, of the base, if desired, may be of extended height to provide a printing or display area, and serving additionally as an aid in assembling the bottles in the carrier crate.

A pair of U-shaped side frames 4 and 5, preferably of wire, are hingedly anchored to the base through the opposing end walls 3, 3. For this purpose the end walls include horizontal slotted apertures 6 located near the corners of the base for receiving the vertical anchor hooks 7 formed at the lower ends of each of the limbs 8 of the side frames. The end walls immediately above the apertures include indentations or insets 9 serving to retain the side frames in partially erected position when they are arranged for loading.

10 The hooks 7 are arranged to be slipped through the horizontal slots lengthwise, with the side frames swung to a lowered position appropriate to dispose the hooks horizontally in line therewith. The hooks lock with the base when the 15 side frames are swung to a normal or erected position, being then disposed substantially crosswise of the slots. The hooks are angled slightly with respect to the limbs, so that the inner portion of the hook is disposed somewhat crosswise 20 of the slot when the frames are in a horizontal position when collapsed for stacking.

The anchorage slots of the end walls simplify assembly of the crate inasmuch as the side frames can be applied by hand, and the hooks 7, 35 as formed, being self-locking, require no further bending or clinching for locking to the base. The indentations 9 in the end walls act as detents to limit the degree of swing and retain the side frames in an intermediate or open position for 40 loading or unloading the crate. When it is desired to collapse the crate, the frames may be forced to snap past the intermediate limit to a horizontal position.

In erected or carrying position, the side frames 45 are disposed in crossed relationship, the limbs 8 intersecting each other, and the respective connecting bars 10 disposed on opposite sides, above and parallel to the base, to confine the bottles. The frames enclose and clasp the bottles, engaging along their upper portions and following the contour of the bottles at opposite ends, and extending angularly across the ends 50 of the crate.

Each connecting bar is configured to provide 55 a pair of offset portions 11 to receive a pair of carrying bails 12 and 13 pivotally anchored thereon, one bail for each respective side frame. The bails are generally of U-form, having a pair of limbs joined by a handle section, the opposite end 60 of each limb including an eye for a hinge con-

nection with the side frame. The bails are dimensioned to fit one within the other, so that one bail, namely 13, may be swung across the top of the crate as a hasp, looped about the other bail 12, which serves as a clasp to draw and lock the frames together.

The bails serve two purposes, in one position serving as carrying bails, and in the other position as clasps, for the side frames. In the first instance the bails are erected providing a convenient hand hold, as illustrated in Figure 2, for carrying a retail supply of beverage bottles. In the second instance the bail 13 is swung in place across the top of the crate forming a hasp, looped over the bail 12 which acts as a toggle to draw the side frames toward each other, to securely clamp the bottles.

The bail 12, serving as a clasp, is looped about the connecting bar 10 being provided with elongated loops or eyes 14 for a binding engagement with the offset handle section 15 of the opposite or hasp bail 13. In clamped position, the offset handle section is disposed below or in off center relation to the connecting bar 10, caught beneath the looped-under section of the eye 14 under clamping pressure, retaining the clasp bail in locked-down clamping position.

As illustrated in Figure 1, for binding or clamping a group of bottles within the tray, the bail 13 extends crosswise of the bottles below the tops thereof, and encloses the centrally positioned bottles of the group. The offset cross bar or handle section 15 of the bail 13 projects downwardly with the angle section 16 of the limbs of the second bail 12 overlying the cross bar 15 of the bail 13. The offset cross bar portion 15 of the bail 13 hooks over the cross bar portion 10 of the frame 4 as a clasp. Upon swinging the bail 12 downwardly to an approximately vertical position at one side of the group of bottles, the angle section 16 together with the oblong eye 14 at the free end thereof pivotally connecting bail 12 to the frame 4, provide for wedging the forward offset end of the bail 13 downwardly with a portion of the eye projected between the offset 11 of the frame 4 and the cross bar 15 of the bail 13, establishing a pressure interlock, holding the bail 12 under pressure against self release, and also brings and sustains the side frames 4 and 5 into clasping engagement with the bottles so that they are securely confined within the case for stacking the units one upon another, of advantage in shipping and storage. The elongated eye connection of the bail 12 with the frame 4 provides the necessary play to permit the interlocking engagement of the bails and firmly holds the bail 13 in its crosswise bottle confining and frame clamping position.

The hand crate may also be carried in a locked position, as illustrated in Figure 4. In this instance the bail 13 is swung in place, as a hasp spanning the side frames and looped over the carrying bail 12 which is in erected carrying position. The crate with the bails in this position is positively locked for carrying.

The cooperating bail arrangement duplicates that described and claimed in a separate application filed on even date hereof and to which, for that reason, no claim is specifically made herein.

Having described my invention, I claim:

1. A hand crate for bottles, comprising: a sheet metal base of tray form to sustain a group of bottles in symmetrical arrangement, a pair of U-shaped wire frames having their limbs nor-

mally disposed in crosswise relation with the ends thereof hingedly attached relatively to the opposite ends of the base, the frames in an operative position inclined across each other, clasping and binding the bottles disposed therebetween, and a bail respectively for each frame disposed midway of and pivotally connected thereto, the bail of one frame engageable through the bail of the second to interconnectingly join and clamp the upper ends of the frames about the bottles, and the second bail when brought outwardly downward to extend toward the base cooperating with the first to lock the same in its frame clamping position.

2. A hand carriage bottle crate, comprising a pan-form base for sustaining a group of bottles in an upright position, a pair of wire frames each constituting a pair of limbs connected by a cross bar extended at an angle thereto for the top of the frame, the limbs of the frames normally in crossing relation with the ends thereof hingedly connected respectively to the opposite ends of the base, adapting the frames to straddle the group of bottles from opposite sides thereof, and a pair of bails each hingedly connected to a respective cross bar of a frame and centrally thereof, one thereof adapted to be interlooped through the second and locked thereby in a horizontal position across the bottles and claspingly connect the upper ends of the frames upon swinging the second bail downward to a perpendicular position alongside the bottles, said second bail in an upward position providing a hand hold for the crate while the first bail is interlooped therewith and bridgingly connecting with the upper ends of the frames.

3. A hand carriage bottle crate, comprising a base for sustaining a group of bottles, a pair of wire frames of U-form having their ends hingedly connected respectively to the opposite ends of the base, the frames in an operative position inclined across each other, straddling the group of bottles from opposite sides thereof, and a pair of bails each hingedly connected to the top of a respective frame and centrally thereof, one thereof adapted to be interlooped through the second and locked thereby in a horizontal position across the bottles and connect the upper ends of the frames, the second bail in an upward position providing a hand hold for the crate while the first bail is interlooped therewith connecting the upper ends of the frames, and adapted to be brought downward to a perpendicular position alongside the bottles to lock the first bail in its frame connecting position.

4. A hand carriage bottle crate comprising a base for sustaining a group of bottles in an upright position, a pair of wire frames pivotally connected respectively to the opposite ends of the base and in an operative position inclined across each other, straddling the group of bottles from opposite sides thereof, a pair of bails each pivotally connected respectively to the top of a frame, one thereof adapted to be engaged through the second and be locked thereby in a horizontal position across the bottles and connect the upper ends of the frames, the second bail in upward position providing a hand hold for the crate while the second bail is interlocked therewith and connecting the upper ends of the frames and adapted to be moved downward to a vertical position along side the bottles to lock the first bail in its frame connecting position.
